CARTRIDGE SHELL

Léon Auguste Guignet, La Varenne Ste. Hilaire, France, assignor to Compagnie Royale Asturienne des Mines, Paris, France, a corporation of Belgium

Application March 1, 1933, Serial No. 659,115
In Germany January 17, 1933

5 Claims. (Cl. 102—12)

This invention relates to drawn metal cartridge shells having a double circumferential fold between the base and the tubular part of the shell. Metal shells in accordance with the present invention are especially suited for sporting cartridges because they are moisture proof and are therefore preferable to the cardboard shells used extensively heretofore. Heretofore the crowns of such double folds were tightly closed so that adjacent layers of the fold touch each other over substantially their entire length. While such folds were intended to strengthen the base, they were not permanently gas tight as the material in the crowns of the fold was over-strained during the manufacture to a point where incipient cracks developed therein which opened up when the cartridge was fired, or the material was weakened to a degree that it could not withstand the firing pressure.

20 The present invention has for its object to provide a cartridge shell which avoids the aforementioned disadvantages.

Another object is to provide a cartridge shell which does not crack upon firing and which therefore can be employed with safety.

Another object is to provide a cartridge shell of relatively light weight in relation to the pressure which is developed therein upon firing.

Another object is to provide a cartridge shell with a double fold between the rim of the base and the tubular part which fold forms an elastic spring-like connection between the parts capable of yielding upon firing and thus reduces the strain upon the shell.

35 Another object is to provide a cartridge shell with a double fold in which the maximum stresses to which the material is subjected during manufacture and during subsequent firing are relatively low.

40 Another object is to provide a cartridge shell of a material which is readily formed, which is inexpensive and which is especially suited for the purpose.

The accompanying drawing illustrates one embodiment of my invention.

In the drawing.

Figures 1 and 2 are longitudinal cross sections of a cartridge shell during different stages of the manufacturing process, while

50 Fig. 3 is a longitudinal section of the lower part of the finished shell.

Referring to the drawing, the shell which has a tubular part 1 and a base 2 is first cold drawn in the usual manner, the bottom having a constant thickness and the wall of the tubular part being

slightly tapered as shown in Fig. 1. It will be understood that the proportions shown in Figs. 1 and 2 are somewhat exaggerated. As an example the thickness of the top end of the tubular part in the stage shown in Fig. 1 may be .23 mm., while the thickness of the tubular part near the base may be .35 mm. and the constant thickness of the base .7 mm.

By subjecting the shell blank to a further operation, it attains the form shown in Fig. 2 where-
in the length of the tube is increased and the bottom is approximately hemispherical. There-
after the blank is put into another tool which gives it its final shape as illustrated in Fig. 3
and in which the double fold between the wall 60
1 and the rim 3 of the base 2 is designated by
the numerals 4 and 5. It will be observed that
the thickness of the wall in the first bend 4
near the rim 3 is slightly tapered and that the
crowns of the fold are given radii which are 65
large in relation to the thickness of the metal
and the sides thereof are oblique to the base.
The cross section of the entire double fold re-
presents a substantially continuous curve as dis-
tinguished from a bend consisting of a combi-
nation of curves and straight lines. By virtue
of this construction, over-straining and crack-
ing of the outside fibers of the turns during man-
ufacture or firing is avoided, and the double fold
when subjected to the lateral and radial gas 70
pressure resulting from firing, yields sufficiently
to reduce the maximum strain upon the material
to a safe value.

I have also found that certain materials are
especially suitable for cartridge shells of the type 90
described herein. Pure zinc, which is readily
worked into the proper shape, is too soft for a
cartridge and will not withstand the firing pres-
sures. Commercial brass is relatively expensive
and cannot readily be drawn into my preferred 95
form. After many experiments I have discov-
ered that an alloy of copper and zinc having a
very high zinc content is especially suitable for
cartridge shells. As an example, an alloy of
99.5% by weight of zinc and .5% by weight of 100
copper is readily shaped and readily withstands
the firing pressure.

While I have specified in the appended claims
an alloy of 99.5% by weight of zinc and .5% by
weight of copper, I do not wish to limit myself 105
to the exact proportion but any alloy of zinc
and copper containing between .4% and 1% of
copper is deemed to come within the scope of
the appended claims.

What I claim as new and desire to secure by Letters Patent is:—

- 5 1. A metal cartridge shell having between its base and its tubular part two resilient folds which are reversed relative to each other, said folds including arcs of more than a half-circle and having relatively large inside radii.
- 10 2. A metal cartridge shell provided with a resilient double fold between the base and the tubular part of the shell, the crowns of said fold having relatively large inside radii, said shell consisting of an alloy of zinc and copper containing approximately .5% by weight of copper.
- 15 3. A metal cartridge shell having between its base and its tubular part two resilient folds which are reversed relative to each other, said folds including arcs of more than a half-circle and having relatively large inside radii, the

change in curvature between the folds being substantially continuous.

4. A metal cartridge shell of an alloy of zinc and copper containing approximately .5% by weight of copper, said shell being provided with a resilient double fold between its base and its tubular part, the cross section of said double fold forming a substantially continuous curve.

5. A metal cartridge shell having between its base and its tubular part two resilient folds which are reversed relative to each other, said folds including arcs of more than a half-circle and having relatively large inside radii, the change in curvature between the folds being substantially continuous, the thickness of the wall along said walls being tapered.
